UNITED STATES PATENT OFFICE.

JOHN CASEY, OF BOSTON, MASSACHUSETTS.

UPRIGHT PIANO-FORTE.

SPECIFICATION forming part of Letters Patent No. 355,001, dated December 28, 1886.

Application filed June 14, 1886. Serial No. 205,107. (No model.)

To all whom it may concern:

Be it known that I, JOHN CASEY, of Boston, in the county of Suffolk, of the Commonwealth of Massachusetts, have invented a new and useful Improvement in Upright Piano-Fortes; 5 and I do hereby declare the same to be described in the following specification, and represented in the accompanying drawings, of which—

10 Figure 1 is a vertical section of part of a piano-front with its music-rest and its operative mechanism in accordance with my invention, the nature of which is defined in the claim hereinafter presented. In this figure the said music-rest is shown as "out," or in a position for use; but in Fig. 2, which is a similar section, the said rest is shown as closed. Fig. 15 3 is a transverse section of the music-rest and its supporting spring-catch.

20 The said music-rest is shown at A as provided at its lower edge with a movable shelf, B, hinged to the said rest, which at top is hinged to the piano-front piece C.

25 At the back of the rest, and in a groove, *a*, formed lengthwise therein, is a metallic rod, D, which, near its upper end, extends loosely through a tubular guide, *b*, fastened to the rest. At its lower end the said rod is hinged to an arm or projection, *c*, extending from the 30 back side and edge of the shelf. A rod or strut, E, hinged at its lower end to the front-piece C, in rear of the music-rest, extends upward, and, at its upper end, is pivoted to the rod D. In rear of the said rod E, and fastened 35 to the front-piece C, is a spring, F, that at its free end bears against the strut E.

To the back of the music-rest, at its lower part, there is fixed a spring-latch, G, which extends across the rod D, and is provided with 40 a stud, *e*, to enter either of two holes, *f* and *g*, made in said rod. A push-button, H, has its shank going through the music-rest and bear-

ing against the spring-catch. On pressing in the said push-button the spring-catch may be forced out of engagement with the rod. By a 45 person applying the thumb or forefinger of his hand against the head of the push-button and pressing it inwardly, when the music-rest is out or in the inclined position shown in Fig. 1, the said catch may not only be forced out of 50 engagement with the rod D, but the music-rest, as well as its shelf, may be forced backward into a vertical position against the front-piece, the shelf while moving backward being caused to turn downward from a position at a right angle to the rack into one in the same plane 55 with it. Both the rest and shelf, when back, will be held in their positions by the spring-catch engaging with the rod D. If when the rest is back the push-button be pressed inward, so as 60 to force the spring-catch out of engagement with the rod D, the spring will at once be free to act, and by its pressure on the strut will force it outward, and thereby cause the music-rest to move forward and the rod D at the 65 same time to descend and cause the shelf to turn into a position at a right angle to the music-rest.

I claim—

In combination with the upright-piano-front 70 piece, the music-rest hinged thereto and the shelf hinged to the music-rest, the arm projecting from such shelf, the slide-rod hinged to such arm and adapted, as described, to the music-rest, the strut or rod hinged to the slide-rod and to the front-piece, the spring secured 75 to such front-piece and bearing against the strut, and the spring-catch and its operating push-button applied to the music-rest, all being substantially as set forth.

JOHN CASEY.
